ABSTRACT OF THE DISCLOSURE

A roof drain provided with a weir plate having a flow metering aperture, the weir plate being vertically adjustable to adjust the size of the aperture.

BACKGROUND OF THE INVENTION

This invention relates to drain structures of the type disclosed in the co-pending application of John E. Ember-
son, United States application Ser. No. 516,470 filed Dec.
27, 1965 now Pat. No. 3,447,329, wherein a weir arrange-
ment is provided for controlling the rate of flow of water
from a flat or gently sloped roof area into the downpipe
and hence into the storm sewer system.

In accordance with the teachings of the said co-pend-
ing application provision is made in the drain by provid-
ing one or more special flow passages which have been de-
scribed as inverted parabolic notches which are sized and
calibrated with respect to the average storm anticipated
to provide the requisite drain flow control for the sys-
tem. By virtue of their shape these notches or apertures
are intended to provide a flow rate which is directly
proportioned to the head of water to provide a controlled
flow through the drain so that the capacity of the down-
pipe and sewer into which it feeds, will not be exceeded.
As a result the roof on which such drains are adapted to
be installed is transformed into a storage reservoir and
the water is metered off the roof at a controlled rate. This
arrangement enables the use of fewer drains than those
with uncontrolled flow rate and smaller diameter down-
piping with smaller sewers can be utilized giving impor-
tant savings in installation costs.

In practice it has been found that it is desirable to
install the roof drain from one quarter to one inch below
the finished roof level with drains of the type disclosed
in the said co-pending application 516,470. When the
drain is set at the variable distance below the roof deck
the bottom of the metering aperture or apertures is auto-
matically placed at a random distance below the roof
deck according to the particular drain installation so
that the calculation of the formulae used in the rating
of the roof drain which are based on the bottom of the
aperture being located flush with the roof level are in-
accurate. This inaccuracy could be quite substantial since
the head of water on the weir could be up to an inch
more than that used in the calculations where the drain
is set at the maximum distance below the roof level.

RELATED INVENTION

The related invention is disclosed in the above-men-
tioned United States application Ser. No. 516,470 filed
Dec. 27, 1965 now Pat. No. 3,447,329.

SUMMARY OF THE INVENTION

Accordingly, it is the object of the present invention
to overcome the above problems encountered with drains
of the flow metering type by providing a drain arrange-
ment where the flow controlling aperture or apertures
can be adjusted to compensate for the distance that the
roof drain is installed below the finished roof level, so
that the drain will provide the actual flow control for
which it was designed.

2

In order to accomplish this object according to the
invention, the drain is provided with what is usually re-
ferred to as a weir arrangement which is vertically ad-
justable so that irrespective of the position of the drain
below the roof deck the bottom of the flow control or
metering passage or aperture or apertures as the case
may be will be level with the roof surface to provide the
requisite flow control in proportion to the head of water
standing on the roof.

BRIEF DESCRIPTION OF THE DRAWINGS

The invention will be better understood with refer-
ence to the accompanying drawings in which FIG. 1 is
a part mid-vertical section, part diagrammatic view of a
5 roof drain installation embodying the invention. FIG. 2
is a broken away perspective view of a drain of the type
15 illustrated in FIG. 1 embodying the invention.

DETAILED DESCRIPTION OF THE INVENTION

20 With reference to FIG. 1 there is illustrated a drain
installation mounted in a roof comprising a deck 1 over
which is applied fill 2 and an overlying covering or sheet-
ing 3. The drain assembly generally designated at 10
15 which is mounted in an opening 4 in the roof deck has
a body 6 clamped between an upper bearing pan 7 and
an underdeck clamp 8 by means of bolts 9. Secured on
the body 6 is a flashing clamp 11 which supports a dome
25 12 that has apertures 13 therethrough that permits the
water to enter the drain while screening out foreign ob-
jects.

30 The flashing clamp 11 carries a base 14 having a large
central opening 17 which has upstanding corner walls 15
which are best seen in FIG. 2. These corner walls define
35 openings 16 in each of four sides defined by the corner
walls in the embodiment of the invention illustrated.

In the absence of any controlling device it will be ap-
preciated that water off the roof would flow into the
drain in essentially uncontrolled flow rates, depending
40 upon the head of water on the roof, the flow being
through the dome which restricts only foreign objects,
through the openings 16 down through the central base
opening 17 into the body 6 and out the outlet 18 pro-
45 vided in the body to the drain system (not shown). Ex-
cessive flow rates through the openings 16 and 17 greater
than the capacity of the drain system could, of course,
cause backing up problems at any point along the drain
system.

According to the present invention means are provided
50 to permit an accurately predetermined flow rate control
through the openings 16, or in a particular case, through
a single opening 16 if flow requirements so necessitate,
irrespective of the location of the flashing clamp 11 relative
to the upper surface of the roof covering 3.

To provide this flow control there is provided one or
55 more weir plates 19 adjustably mounted on the walls 15
extending upwardly from the base 14 so that they can be
moved vertically to adjusted positions and then set against
dislodgement. In this connection it will be seen that each
60 of the weir plates 19 is provided with a pair of slots 20
through which operate clamping screws 21 to clamp the
weirs in adjusted vertical positions on the walls 15. Each
65 of the weir plates 19 is provided with a flow controlling
passage or aperture 22 of the "parabolic" type. These
apertures are defined by side walls 23a and 23b which
lie on the curve of a parabola, the walls being widely
70 separated at the bottom then rapidly approaching each
other towards a knee 24 and then asymptotically approaching
each other towards the top.

It has been found that the flow rate through such an
75 opening or aperture 22 is directly proportional to the
head of water standing against the weir plate 19. It will
be understood however that in making calculations as

to the flow rate through the aperture in designing a drainage system, the aperture bottom 25 is assumed to be at the bottom of the water head, that is, level with the roof covering 3 and the flow calculations through such a metering opening 22 are inaccurate the moment that the bottom of the opening 22 is displaced above or below the roof level.

According to the present invention therefore, the drainage system may be made to provide the flow rate in accordance with the design calculations for the system by providing for the adjustment of the weir plates 19 through the use of the slots 20 and clamping screws 21 to bring the bottoms of the metering openings 22 flush with the roof covering 3.

It will be appreciated that the actual volume of flow through the drain will depend upon the number of weir plates 19 which are employed. In FIG. 2 there are illustrated two such weir plates. However, the corresponding openings on the other side of the base (not shown) may if desired be closed by plates corresponding to the weir plates 19 but omitting the metering openings 22.

For sake of convenience provision is shown for the mounting of say 4 metering weir plates 19 but it will be understood that the actual physical shape of the weir mounting means, that is the support comprised by the base 14 and walls 15, may vary at will, the only requirement being that there be provided a mounting on which a weir plate having a metering orifice is vertically adjustable so that its bottom may be set relative to the upper surface 3 of the roof deck.

In practice the vertical variations in the mounting of the drain relative to the upper roof surface 3 are something of the order of one inch and the vertical adjustment of the weir plates 19 is made to provide for full vertical adjustment to the extent of drain installation variations likely to be encountered.

I claim:

1. In a drain structure for removing water from a surface area an upstanding support having an opening therethrough leading to the interior of the drain, a weir plate mounted on said upstanding support and overlying said

opening said weir plate having a flow metering aperture therein extending upwardly from a substantially horizontal base and forming a flow restricting means through said support opening, and means for providing vertical adjustment of the weir plate to vertically adjust the position of the base of said aperture relative to a surface area to be drained.

5 2. A device as claimed in claim 1 in which said weir plate is slotted and is secured to said upstanding support for vertical adjustment by clamping screws passing through said slots and into said wall.

10 3. A drain structure for removing water from a surface area with a controlled flow rate comprising a drain body having a drain outlet, an upstanding wall having an opening 15 through which water from such surface area must pass to reach said drain body and outlet, and means controlling the flow of water through said wall opening, said means comprising a plate mounted on said upstanding wall across said openings, said plate having a flow regulating aperture formed therein, said aperture extending 20 upwardly from a substantially horizontal base, and means mounting said plate for vertical adjustment whereby said substantially horizontal base of the flow controlling aperture is adapted to be vertically adjusted relative to a surface 25 area to be drained.
